DISCHARGE TUBE

Baarte Krol, Mitcham Junction, England, assignor to N. V. Philips' Gloeilampenfabrieken, Eindhoven, Netherlands

Application May 20, 1936, Serial No. 80,690
In Great Britain May 28, 1935

2 Claims. (Cl. 250—27.5)

My invention relates to electric discharge tubes, and more particularly to means for supporting various members of such tubes.

My invention is particularly adapted for supporting heating filaments, and I shall describe same in this connection; however it should be understood that my invention is in some cases applicable to the support of other electrodes, for instance a grid formed by a wire wound in zigzag fashion in substantially one plane.

I shall describe my invention in connection with the supports of heating filaments, for example as are used in radio receiving tubes operated from storage batteries.

In present-day battery-operated radio receiving tubes, the filaments are generally formed in zigzag fashion in the shape of a V, W or similar figure. Although the two ends are suitably supported from the pinch, it is also necessary to support or suspend the filament at those points at which the filament changes its direction, i. e. at the apex or apices of the zigzag winding. Such supports are intended to prevent vibration of the filament, which, as is well known, would cause so-called "microphonic" noises and increase the allowable electrode spacings. For this purpose it has been proposed to use supporting means, such as hooks, at least one of which is resilient or is provided with a spring to tension the filament, with or without mica spacers which cause a tension in the filament. Such tensioning of the filament is very undesirable, and in addition the use of hooks produces local cooling whereby the electron emission is considerably reduced.

My invention obviates, or at least considerably reduces, such difficulties as have been above pointed out, and provides a simple and effective support for filaments and other electrodes.

According to my invention a directly-heated filament, for example, is compressively supported, without tensioning, between two or more supports of an electrically-insulating and poorly heat-conductive substance, such as mica or the like, which supports are in turn supported within the tube.

With such a support the electrode spacing, for example, the distance between the filament and grid, may be reduced to a very small value without any difficulties, while at the same time, due to the absence of hooks and the like, and with a suitable design of the supports, the cooling of the filament may be very considerably reduced and tensioning of the filament completely avoided.

In order that my invention may be clearly un-

derstood and readily carried into effect, it will be more fully described with reference to the accompanying drawing, in which:

Figure 1 is a partly sectionized side elevation on an enlarged scale of a portion of a thermionic tube embodying my invention;

Figure 2 is a side view of Figure 1;

Fig. 3 is a sectionized view of Fig. 1 taken along line III—III;

Fig. 4 is a sectionized view of Fig. 1 taken along the line IV—IV;

Figs. 5 and 6 are side views of supporting members for filaments of other shapes;

Fig. 7 is a perspective view of a complete thermionic tube utilizing my invention.

As shown in Figs. 1-4, a directly-heated filament or cathode 10 is arranged in a plane in zigzag formation, and has its ends connected by wires 11 to conductors 12 sealed into a pinch 13 forming part of the evacuated envelope 39 of 20 the tube which is provided with an ordinary base 40 and contact pins 41, as shown in Fig. 7.

The filament 10 is arranged between and supported by two rectangular plates or sheets 14 of an electrical insulating and poorly-heat-conductive material, for instance mica, provided with rectangular apertures 15 through which the major portion of the filament is exposed. The apertures 15 are so shaped and the filament 10 is so positioned therebetween that the points at 30 which the filament changes its direction are gripped or clamped between the two adjacent sheets 14, whereas a portion of the filament between those points is held between the bars 16 remaining between the apertures of each sheet. 35 The filament is thus held firmly in position without any tensioning thereof.

A filament for use with the present invention may be formed by winding a wire, for instance, in a suitable jig into a zigzag form, flattening the 40 zigzag wire by applying pressure normally to the plane of winding, activating the so-formed zigzag wire, for instance by spraying, and subsequently clamping the wire between the supports and mounting it on the pinch; or alternatively 45 first mounting the wire on the pinch and then clamping it between the supports.

Provided along each vertical marginal edge of the two sheets 14 is a U-section metal stiffener 50 and spacer 17, whereas another U-shaped clip 18 serves to clamp the sheets together and also to firmly hold the connecting wires 11 and maintain them accurately in position.

The mounting of the two sheets 14 is effected 55 by clamping each vertical edge thereof, with the

stiffening member 17 in place, between two vertical metal clamping strips 19 whose lower ends are mounted in metal supports 20 sealed into the pinch 13. As shown, the clamping strips 19 are formed as two opposing strips which are spot-welded together at their ends, however a single strip bent back upon itself may be used for this purpose. In addition to acting as supports the clamping strip 19 may also serve as leads for the filament connections. Furthermore, the U-section members 17 also serve to inter-space the two sheets 14 when these sheets are clamped between the vertical strips 19, whereby the filament 18 is held snugly at all points without undue pressure, and as a result excessive heat losses at the points of contact between the filament and the supports 14 are avoided.

The support strips 19 are conveniently arranged as part of or the support for, one of the other electrodes of the tube. As shown in Figs. 1-4, the grid structure of the tube consists of a plurality of wires 21 spot-welded or otherwise secured to the inner surface of the vertical strips 19 with the aid of metal strips 22. With such a construction the spacing between the filament and the grid can be reduced to a very small amount without any difficulty.

Instead of using a grid of the above construction, the grid, or similar structure, may be formed by winding the wires around the mica sheets 14 before mounting them between the strips 19 and members 17.

In addition to supporting filaments of the shape shown in Figs. 1-4, the invention is applicable to filaments of other shapes.

As shown in Fig. 5, a V-shaped filament 32 having long straight portions is supported between support plates 30. The supports 30 are similar to the supports 14 of Figs. 1-4 with the exception that they have four rectangular apertures 31 separated by ribs 23.

As shown in Fig. 6, a filament 33 of a spiral shape is supported between plates 34. The plates 34 are similar to the plates 10 of Figs. 1-4 with the exception that they are provided with sector-shaped apertures 35 separated by radially-extending ribs 24. To facilitate bringing out the lead wires, the filament 33 is formed of a single wire wound double, the ends 36 and 37 of the wire 50 acting as the leads.

Instead of clamping the filament between apertured mica sheets and using the frame construction shown, various other constructions may be used. For instance, the filament may be clamped between pairs of straight mica strips held to-

gether at their ends by pairs of E, F, or L-shaped members. Furthermore, in addition to using clamps at the edges of the mica sheets, the sheets may be held together at intermediate points by eyelets, as indicated at 38.

Furthermore, when supporting a grid or other electrode, the clamps on the edges of the mica sheets may be provided with notches or slots.

In addition to supporting bent filaments of the type shown in the drawing, the invention is also adapted for supporting linear filaments. For example, in the case of a magnetron it may be desirable to support the filament at intermediate points. As in such cases the anode is usually split into two portions, the clamp may 15 extend between these portions.

To increase the active emitting surface and to facilitate clamping, the filament is preferably flattened, i. e. formed as a narrow strip or ribbon.

While I have described my invention in connection with specific examples and applications, I do not wish to be limited thereto, but desire the appended claims to be construed as broadly as permissible in view of the prior art.

What I claim is:

1. An electric discharge tube comprising an envelope having a pinch, a filamentary electrode, lead wires electrically connected to said filament and sealed in said pinch, and means for supporting said electrode from said pinch comprising a plurality of relatively thin perforated plates of electrical insulating material of poor thermal conductivity, said electrode and lead wires being clamped between said plates with the electrode 30 in registry with said perforations, and a plurality of fastening means for holding said plates together, one of said means being disposed near said lead wires to rigidly hold same between said plates.

2. An electric discharge tube comprising an envelope, a folded filamentary electrode arranged in a plane, a grid electrode, means for compressively supporting said filamentary electrode comprising a plurality of perforated plates of 45 electrical insulating material of poor thermal conductivity, and a plurality of metal supports attached to the edges of said plates for supporting said plates and for holding said plates together, said supports attached to and holding said grid electrode over said perforations in co-operative relation with the filamentary electrode.
